UNITED STATES PATENT OFFICE

JESSE G. ZIM, OF MEDFORD, MASSACHUSETTS, ASSIGNOR OF FIFTEEN PER CENT TO JOHN F. SHEEHAN, OF EVERETT, MASSACHUSETTS, FIFTEEN PER CENT TO WILLIAM C. GRAY, OF CAMBRIDGE, MASSACHUSETTS, FIFTEEN PER CENT TO LEON W. RICH, OF MEDFORD, MASSACHUSETTS, AND TEN PER CENT TO JOHN P. BUCKLEY, OF BOSTON, MASSACHUSETTS

PROOF-READER'S TABLE

Application filed February 13, 1928. Serial No. 253,853.

This invention relates to a table construction and has for its object the provision of a table adapted for general uses and which may be readily converted to meet the needs of a proof reader.

In accordance with the invention the table top is provided with an opening having a suitable closure mounted therein which may be supported in the opening in an inverted inclined position to serve the needs of a proof reader. In the preferred construction means are provided for adjustably positioning and supporting the closure in its inverted inclined position.

15 Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation, and it is not intended to limit the invention beyond the terms of the several claims hereto appended or the requirements 30 of the prior art.

The invention will be more clearly understood from the following description in conjunction with the accompanying drawings, in which

35 Figs. 1 and 2 are plan and elevational views respectively of a table embodying the invention;

Fig. 3 is a sectional view taken upon the line 3—3 of Fig. 1;

40 Fig. 4 is a sectional detail view showing the arrangement for locking the closure in closed position; and

Fig. 5 is a detail view partly in section showing the relation of various parts of the 45 table.

As illustrated in the drawings, the table may comprise a table top 10 supported in raised position in any appropriate manner, as by legs 11. The table top is provided 50 with an opening 12 in which a suitable clo-

sure 13 is mounted. If desired, a drawer 14 may be slidably mounted below the opening 12 and for this purpose spaced guides 15 are secured to the underside of the table top in any well known manner and are arranged to engage guideways 16 in the drawer.

A suitable arrangement for mounting or supporting the closure 13 in the opening 12 may include a slide, such as an eye-head bolt 18, pivotally mounted in opposite side edges 60 of the closure near one end thereof and operatively connected with suitable guideways, such as rods 19, mounted in the table top adjacent the opposite side edges of the opening 12. The closure may be held in any 65 desired inverted inclined position by a suitable support which may include; for example, a rod 20 pivotally mounted in suitable bearings, such as eye-headed bolts 22 secured in the rear end 23 of the drawer. 70 The rod 20 is provided at each end with an arm 25 extending at right angles therefrom and provided at its free end with a projection 26 adapted to enter any of a plurality of openings 27 in the side edge of the closure. 75 The underside 30 of the closure may be provided with a smooth hard surface in order to meet the needs of a proof reader, and for this purpose it may be glazed.

In order that the closure may be held securely in closed position when it is desired to use the table for general purposes, a suitable catch or lock may be provided. For this purpose a groove 31 may be formed in the under side 30 of the closure. A plate 32 may be suitably secured, as by tacks 33, to the under side of the closure with its edge overlapping a portion of the groove 31. A suitable hook may be positioned in the top edge of the drawer to cooperate with the groove 31 and plate 32 to hold the closure in closed position. Thus, a nail 34 having a relatively large head 35 may be driven into the top surface of the drawer with the head spaced therefrom an amount sufficient to permit it to pass into the groove 30 at a point above the plate 32 when the drawer is moved toward the plate. If desired, a lock 36 may be provided for locking the 100

drawer and preventing its movement relative to the table top.

When the closure 13 is in closed position, as shown in Fig. 4, the table may be used for any purpose desired for which tables are commonly employed. In order to bring the closure to an inverted inclined position to meet the particular needs of a proof-reader, the drawer is moved to disengage the plate 32 and head 35 of the nail. The forward edge of the closure is then raised slightly as shown in dotted lines in Fig. 3, this being permitted by the pivotal connection between the closure and the slide 18. The closure is then drawn forward to bring its rear edge near the forward edge of the opening in the table top and is turned about the slide 18 to an inverted position as shown by the full line position or dotted line position adjacent thereto in Fig. 3. The drawer 14 may be moved forward if desired. The arms 25 of the rod 20, which normally rest within the drawer, are then raised to bring the projections 26 into engagement with any desired corresponding openings 27 in the opposite edges of the closure. The position of the closure may then be adjusted by either moving the slide 18 along the ways 19 a desired amount or by moving the drawer 14 forwardly or rearwardly, thereby changing its position relative to the table top and closure.

In ordinary uses the top surface of a table becomes marred, especially when in use around printing establishments and the like, and is therefore unsuitable for use by proof-readers whose duty it is to find and correct errors in the printing. The difficulties there encountered are eliminated by the provisions of the invention by bringing the smooth hard underside of the closure into suitable position for use. Furthermore, the closure may be adjustably supported to bring it to any inverted inclined position most convenient for the proof-reader. When the table is not in use by the proof-reader the closure may be returned to its closed position and the drawer moved to bring the cooperating parts in the drawer and closure into engagement to hold the closure in closed position. If desired, the drawer may be locked against forward or rearward movement thus rendering the closure a rigid part of the table top.

What I claim is:

1. In a table, the combination with the table top having an opening, a closure for said opening, a drawer slidably mounted below said opening, a slide pivotally connected with said closure, slideways cooperating with said slide mounted in said table top adjacent the edges of said opening, and means for holding said closure in an inverted inclined position in said opening including

a support pivotally mounted in said drawer and adapted to engage said closure.

2. In a table, the combination with the table top having an opening, a closure for said opening, a drawer slidably mounted below said opening, a slide pivotally connected with said closure, slideways cooperating with said slide mounted in said table top adjacent the edges of said opening, and means for holding said closure in an inverted inclined position in said opening including a support pivotally mounted in said drawer and adapted to engage said closure, and cooperating means in said closure and drawer for locking the former in closed position.

3. In a table, the combination with the table top having an opening, a closure for said opening, a slideway in said table top, a slide engaging said way and pivotally connected with said closure, and an arm pivotally and slidably mounted in said table and adapted to engage and hold said closure in an inverted inclined position relative to said table top.

4. In a table, the combination with the table top having an opening, a closure for said opening, a slideway in said table top, a slide engaging said way and pivotally connected with said closure, an arm pivotally mounted in said table and adapted to engage and hold said closure in an inverted inclined position relative to said table top, and means for adjusting the position of said arm relative to said closure.

5. In a table, the combination with the table top having an opening, a closure for said opening, a slideway in said table top, a slide engaging said way and pivotally connected with said closure, an arm pivotally mounted in said table and adapted to engage and hold said closure in an inverted inclined position relative to said table top, and cooperating means in said closure and table for locking the former in closed position in said opening.

6. In a table, the combination with the table top having an opening, a closure for said opening, and means for supporting said closure in said opening in an inverted inclined position including an arm slidably and pivotally connected with said table and adapted to engage said closure.

In testimony whereof I affix my signature.

JESSE G. ZIM.
